EY

OR D 14,272

Design No. 14,272, dated September 11, 1883.

UNITED STATES PATENT OFFICE.

ALBERT PATITZ, OF MERIDEN, CONNECTICUT, ASSIGNOR TO THE BRADLEY & HUBBARD MANUFACTURING COMPANY, OF SAME PLACE.

DESIGN FOR A SCONCE-FRAME.

SPECIFICATION forming part of Design No. 14,272, dated September 11, 1883.

Application filed July 16, 1883. Term of patent 7 years.

To all whom it may concern:

Be it known that I, ALBERT PATITZ, of Meriden, in the county of New Haven and State of Connecticut, have invented a new Design for 5 Sconce-Frames; and I do hereby declare the following, when taken in connection with accompanying drawing and the letters of reference marked thereon, to be a full, clear, and exact description of the same, and which said 10 drawing constitutes part of this specification, and represents a face view.

This invention relates to a design for mirror-frame made from metal, and such as commonly called a "sconce;" and the design consists in 15 the configuration and ornamentation as shown in the accompanying illustration. The shape or general outline of the frame is that of a parallelogram. Each side of the frame is composed of two parallel bars extending from the 20 bottom part to the top part of the frame. The space between the bars of each side is filled by floriated tracery, as shown. At the center of each side is a cross-bar which projects outward beyond the edge of the frame, the face 25 of the cross-bar having a series of rose orna-

ments. The top piece is composed of a horizontal bar, having in the central part of it two bars, connected by a crown-piece, forming a panel, which is filled with a diamond-shaped figure having a rose ornament thereon. At 30 each side of this central portion a bar extends horizontally, connected with the bar below, forming wings or side panels of less height than the center, filled with floriated ornamentation, as shown. The bottom part is the 35 same as the top part, as shown in the accompanying illustration.

I claim—

The design for sconce, consisting of the frame, each side composed of parallel bars, the space 40 between filled with a floriated tracery, and connected at the top and bottom by a center-piece with a wing at each side, showing a rose ornament at the center and floriated tracery at each side, as herein described, and shown in the 45 accompanying illustration.

ALBERT PATITZ.
